SHIZU WADAKUMA, OF LOS ANGELES, CALIFORNIA.

KEY-HOLE COVER LOCK.

BEST AVAILABLE COPY

Application filed October 6, 1925. Serial No. 36,820.

This invention relates to an improved lock device particularly adapted to be inserted in and to close a key-hole, so that an ordinary lock cannot be tampered with by an unauthorized person.

The object of the invention is to provide a simple arrangement of lock mechanism, adapted to be inserted in a key-hole, and to be so constructed whereby a certain number of sliding members on the exterior must be actuated each a certain number of times to release corresponding pawls within the device which hold the locking elements in their locked position.

15 My invention relates especially to lock devices adapted to close a key-hole in the doors of dwelling houses, stores and the like, and has for its particular feature the provision of secret means for operating the locking elements to their unlocked position, spring-actuated locking pawls for the locking elements, cam-levers projecting from the exterior of the device, and spring-actuated cams for lifting the locking pawls to an operative position and adapted to be released by the projecting levers.

To the accomplishment of the foregoing and such other objects as may hereinafter be made to appear, the invention consists in features hereinafter described and defined by the claims.

In the drawings, Figure 1 is a front elevation of my improved key-hole cover lock. Fig. 2 is a vertical and sectional view of the same. Fig. 3 is a front view showing the interior, the cover being removed to show the first partition plate. Fig. 4 is a front view with cover and first partition plate removed. Fig. 5 is a front view with the cover, and first, second and third partition plates removed. Fig. 6 is a perspective detail view of the spindle adapted for actuating the locking plungers to their operative and inoperative positions. Fig. 7 is a front view showing the fifth partition plate. Fig. 8 is a front view showing the sixth partition plate. Fig. 9 is a front view showing the seventh partition plate. Fig. 10 is a detail view of a spring adapted for actuating a locking pawl. Fig. 11 is a plan and sectional view of the device on a plane passing through the lock-actuating spindle. Fig. 12 is a detail view of a ratchet cam shaft. Fig. 13 is a detail view of a ratchet cam. Fig. 14 is a detail plan view of a sliding plunger adapted for actuating a gripping element.

Fig. 15 is a side and detail view of a key-hole gripping element. Fig. 16 is a detail view of a cam lever adapted for releasing certain pawls within the device. Fig. 17 is a perspective detail view of a bar adapted to support the sliding plungers. Fig. 18 is a perspective view of the outer casing portion forming the side walls and top and bottom walls of the device. Fig. 19 is a detail view of the rear wall member, showing the outer side thereof. Fig. 20 is a perspective and detail view of the innermost spacing member.

Referring to the drawings, the rectangular frame member 21, having the top 22, bottom 23 and side walls 24 and 25, together with the front wall member 26 and rear wall member 27, form a casing to contain the operative parts of my improved locking device. Three screws 28, extend through holes 29 in rear wall member 27, and engage with the front wall member 26. Two screws 30, extend through holes 31 in the first inner partition plate 32, and engage with the rear wall member 27. Clearance holes 33, are provided in each partition member, for screws 28, and clearance holes 34, are provided for screws 30.

Between the first partition plate 32 and the second partition plate 35, are mounted the ratchet wheel 36, and the respective pawls 37, 38 and 39, adapted to engage with ratchet wheel 36. The wheel 36, is mounted on the operating spindle 40, provided on the exterior with a handle 41, and on the interior with a cam disk 42, having arcuate slots 43, for the purpose hereinafter set forth. The pawls 37, 38 and 39, are pivotally mounted on bearing shafts 44, which engage with corresponding holes 45, located, respectively, in partition plates 32 and 35. Rotatable disks 46, are fixed to and rotate synchronously with corresponding disk shafts 47, each disk having a series of holes 48, and having each an adjustable cam member 49, which may be set by inserting a fixed pin 50, on each cam member 49, in one of the holes 48. The pawl 37, at the top, has an arm 51, adapted to be actuated by cam member 49, and pawls 38 and 39, are provided, respectively, with arms 52 and 53. Springs 54, secured between the flange 55, on partition member 35, and abutments 56, 57 and 58, fixed to partition plate 38, serve to actuate the respective pawls 37, 38 and 39, into engagement with ratchet wheel 36.

Between partition plates 59 and 60, constituting respectively, the third and fourth partition plates, are mounted the ratchet disks 61, 62 and 63, mounted on disk shafts 47, fixed thereto and adapted to rotate synchronously therewith. Pawls 64, 65 and 66, respectively, serve to prevent rotation, in one direction, of ratchet disks 61, 62 and 63, while sliding pawls 67, 68 and 69, serve to 10 actuate the disks in the opposite direction. Finger members 70, 71 and 72, respectively, serve to actuate sliding pawls 67, 68 and 69. Springs 73, fixed to respective finger members, tend to maintain the sliding pawls in 15 engagement with respective disks 61, 62 and 63. Retaining pawls 64, 65 and 66, are pivotally mounted on bearing shaft 74, which have their extremities 75, in engagement with holes (not shown), in partition plates 59 and 60. An abutment 77, on fourth partition wall 60, serves to hold the springs 78, which actuate retaining pawls 64, 65 and 66. Pawls 67, 68 and 69, have their extremities 79, sliding on abutment 77. 20 Between the fourth partition plate 60 and fifth plate 80, are positioned the ratchet cam members 81, fixed on disk shafts 47. Plate 80 has integral projections 82, serving as stops for cam members 81, the arrangement being such that, on releasing disks 61, 62 and 63, the adjustable cam members 49, are returned to their initial position. To release the members 49, and allow them to return to initial position, I provide pawl-releasing levers 83, 84 and 85. A single movement 25 of lever 83, releasing retaining pawl 64 and sliding pawl 67; a movement of lever 84, serving to release retaining pawl 65 and sliding pawl 68; and a movement of lever 84, releasing pawl 66, and sliding pawl 69. Pawl releasing levers 83, 84 and 85, are pivotally mounted on shafts 86, having their extremities 87, journaled in partition plates 59 and 60. 30 The sixth partition plate 88, has recessed portions 89, containing springs 90, which serve to actuate the respective disks 61, 62 and 63, the rotatable disks 46, the ratchet cam members 81, and the shafts 47, on which they are mounted. Springs 90 have one extremity engaging with the pin 91, on each of shafts 47, and their outer extremity 92, in a corresponding slot 93. The spacing member 94 is positioned between the sixth partition plate 88 and the rear wall member 27; this spacing member being shown in Fig. 9. 35 To secure the device to and within a key-hole, I provide key-hole gripping elements 95, which extend outwardly from an opening 96, in the rear wall member 27, and which are adapted to enter into and engage with the edges of the escutcheon plate 97, around the key-hole. For actuating the gripping elements 95, I provide sliding 40 plungers 98, having a pivotal connection with the gripping members; the gripping members having hinge knuckles 99, and the plungers having corresponding hinge knuckles 100, connected by suitable pin 101. The gripping members 95, have integral trunnion shafts 102, which are journaled in transversely extending brace bars 103, spaced apart by spacing member 94. Each plunger 98 has a projecting pin 104, engaging with an arcuate slot 43, in cam disk 42. To insure a sliding movement of the plungers 98, I provide the brace bars 103, with projecting ramps 105, on which the plungers slide, and I provide a seventh partition member 106, having slots through which the pins 104, extend. Slots 107, in spacing member 94, determine the position of brace bars 103, and of the seventh partition member 106. When the device is assembled, the casing members together, form slots 108, for the finger members 70, 71 and 72, and form slots 109, for pawl-releasing levers 83, 84 and 85. The spacing member 94, has an opening 110, for the gripping members 95. 45 In use, the device is placed over a key-hole, with the locking elements extending therein. The spindle is then rotated. This serves to draw the opposed plungers inwardly and thereby actuates the locking elements, causing them to diverge and thus engage with the edges of the key-hole. The three finger levers that extend from the casing are then actuated. This serves to release the detent pawls and also the sliding pawls, allowing the several rotatable disks or tumblers 46 to assume their initial and inoperative position, and actuating the cam members 49, carried by the tumblers, to their initial position. The ratchet pawls 87, 88 and 89, when 50 released by cam members 49, engage with ratchet wheel 36, thereby holding the spindle from further turning movement, and maintaining the locking members in their operative or gripping position. The device 55 then remains attached to the key-hole escutcheon plate, and covers the key-hole. 59 To release the device, the uppermost finger member 70, is actuated successively with a reciprocating movement, until the corresponding cam lever 49, has moved to operative position beneath the uppermost ratchet pawl 87, disengaging the same from wheel 36. Finger member 71, is then successively 60 actuated until pawl 88 is released from ratchet wheel 36, and similarly finger member 72 is actuated to release pawl 89. The spindle 49, may then be rotated, thereby drawing the plungers 98 apart, and drawing the locking members 95 together, so they may be withdrawn from the key-hole. The device 65 may be set to various combinations of numbers, by changing the position of each cam lever 49 relative to its corresponding disk 320 or tumbler 46. 70

From the foregoing description and drawings, it may be seen that I have provided an efficient cover for closing ordinary key-holes, and means for locking the cover in its operative position.

What is claimed is:

1. In a lock, a casing, lock elements extending therefrom and having an operative position and an inoperative position, a rotary spindle adapted for actuating the lock elements to their operative and inoperative positions, a handle on the exterior of the casing for actuating the spindle, a ratchet wheel on the spindle, ratchet pawls in engagement with the ratchet wheel, and serving to prevent rotation thereof, spring-actuated and rotatable tumblers mounted within the housing, stops extending within the casing and limiting the rotary movement of the rotatable tumblers and determining their initial position, cam levers carried by the rotatable tumblers and adapted to disengage said ratchet pawls from said ratchet wheel when the rotatable tumblers are actuated from their initial to their operative position, sliding ratchet pawls arranged to actuate the tumblers successively from their initial to their operative position, other ratchet pawls serving to prevent contrary rotation of the tumblers during their actuation by the sliding ratchet pawls, finger members slidably mounted on the exterior of the casing for manipulation of the sliding ratchet pawls, and pawl-releasing levers extending from the casing and adapted to release both the sliding ratchet pawls and the retaining pawls to allow the rotatable tumblers and the cam levers carried thereby to return to their initial position.
2. In a lock, a casing, lock elements extending therefrom and having an operative position and an inoperative position, a rotary spindle arranged to actuate the lock elements to their operative and inoperative positions, a ratchet wheel integral with the rotary spindle, spring-actuated pawls in engagement with the ratchet wheel and serving to prevent rotation thereof, means for disengaging said spring-actuated pawls from said ratchet wheel, said means having an initial position and an operative position, means for actuating the disengaging means with a step by step movement from initial position to operative position, and means for releasing the disengaging means when in its operative position to allow return to initial position.
3. In a lock, a casing, lock elements extending from the casing and having an operative spaced apart position, and having an inoperative position, a rotary spindle arranged to actuate the lock elements to their operative position and to their inoperative position, a ratchet wheel mounted on said spindle, detent pawls in engagement with the ratchet wheel and serving to prevent rotation thereof, spring-actuated and rotatable tumblers mounted within the housing and having an initial position, a cam lever carried by each tumbler and adapted to be adjusted to and from the initial position, means for successively actuating each tumbler and its corresponding cam lever to operative position to disengage a detent pawl, and releasing means for the actuating means whereby the tumblers and their corresponding cam levers are returned to their initial position.
4. In a key-hole cover lock, a casing, lock elements extending from the casing and having an inoperative position, and having a spaced apart operative position, a spindle rotatably mounted in and extending from the casing and adapted for actuating the lock elements to their operative and inoperative positions, a handle on the spindle and disposed on the exterior of the casing, a ratchet wheel mounted on the spindle, ratchet detent pawls in engagement with the ratchet wheel and serving to prevent rotation thereof, spring-actuated and rotatable tumblers mounted within the casing, ratchet cam members rotatable synchronously with the rotatable tumblers, stop elements extending within the casing and projecting in the path of the ratchet cam members to determine the initial and inoperative position of the rotatable tumblers, cam levers carried by the rotatable tumblers and adapted to disengage the detent ratchet pawls from the ratchet wheel in the operative position of the tumblers, sliding ratchet pawls arranged to successively actuate each tumbler from its initial to its operative position, a ratchet pawl for each tumbler and arranged to prevent a contrary rotation thereof, finger members slidably mounted upon the casing, each finger member arranged to actuate a sliding ratchet pawl, a spring fixed to each finger member and serving to hold the corresponding sliding ratchet pawl in operative position, and pawl releasing levers extending from the casing, and adapted to release the sliding pawls and corresponding retaining pawls simultaneously to allow the tumblers and their corresponding cam levers to return to initial position.
5. In a key-hole cover-lock, a casing, lock elements extending from the casing and adapted in their spaced apart and operative position, to engage with a key-hole, a plunger for each lock element slidably mounted within the casing, and having a hinge connection with the lock element, a spindle rotatably mounted in the casing and extending therefrom, a handle on the spindle and disposed on the exterior of the casing, a cam disk on the inner end of the spindle and having arcuate slots, a pin projecting from each plunger and engaging with an

arcuate slot whereby the lock elements are actuated to operative and inoperative positions on rotation of the spindle, detent means to prevent rotation of the spindle, rotatable tumbler mechanism for releasing the detent means, and slideable ratchet element for actuating the rotatable tumbler mechanism to operative releasing position.

6. In a key-hole cover lock, a casing, key-hole gripping elements projecting therefrom and adapted to be actuated to an angularly diverging position to grip the edges of the key-hole, sliding plungers mounted within the casing, and adapted to actuate said gripping elements to their gripping position, cams integral with the plungers, a disk having arcuate slots adjacent to the plungers, said plunger cams engaging with said arcuate slots, a spindle extending from the casing and fixed to said slotted disk, a ratchet wheel on said spindle and located within the casing, ratchet pawls adapted to engage with the ratchet wheel to prevent movement thereof, means for disengaging said ratchet pawls, means for actuating the pawl releasing means successively from an initial position to disengaging position, levers extending from the casing and adapted to be manually actuated to release the pawl-releasing means, and springs serving to actuate the pawl releasing means to initial position when released by said levers.

7. In a key-hole cover lock, a casing, key-hole gripping elements projecting from the

casing and adapted to engage with the edges of the key-hole, sliding members for actuating the gripping elements, a rotatable spindle arranged for actuating the sliding members, ratchet pawl mechanism for preventing rotation of the spindle, releasing means for the ratchet pawl mechanism having an initial position and having an operative releasing position, spring elements tending to return the releasing means to initial position, means for successively actuating the pawl releasing devices to operative position, and means for releasing the said actuating means whereby the releasing means for the pawl mechanism is returned to initial position and whereby the pawl mechanism is returned to operative position.

8. The combination with a casing, of gripping members projecting therefrom and adapted to engage with the escutcheon plate and to extend in the key-hole therein, means for actuating the gripping members to their gripping position, means for locking the actuating means in operative position, including spring-actuating locking pawls and spring-actuated slideable pawls, and releasing levers interposed between the said locking pawls and the slideable pawls, and extending from the casing, said releasing levers being adapted to release the slideable pawls and the locking pawls simultaneously.

In testimony whereof, I hereunto affix my signature.

SEIZI TADAKUMA.
